UNITED STATES PATENT OFFICE.

WILLIAM M. PARKER, OF PARKERSBURG, WEST VIRGINIA, ASSIGNOR TO J. H. PARKER & SON, INCORPORATED, OF PARKERSBURG, WEST VIRGINIA, A CORPORATION OF WEST VIRGINIA.

DESIGN FOR A PLURAL SOCKET.

53,640.

Specification for Design.

Patented July 22, 1919.

Application filed March 22, 1919. Serial No. 284,507. Term of patent 14 years.

To all whom it may concern:

Be it known that I, WILLIAM M. PARKER, residing at Parkersburg, in the county of Wood and State of West Virginia, have invented a new, original, and ornamental Design for a Plural Socket, of which the following is a specification, reference being had to the accompanying drawing, forming part thereof, in which—

Figure 1 is an elevation of a plural socket embodying my design;

Fig. 2 is a plan view thereof; and

Fig. 3 is an end elevation thereof.

What I claim is:

The ornamental design for a plural socket as shown.

WILLIAM M. PARKER.
